UNITED STATES PATENT OFFICE.

SOLOMON B. ELLITHORP, OF ROCHESTER, NEW YORK.

BRAN AND FEED PACKER.

SPECIFICATION forming part of Letters Patent No. 295,863, dated March 25, 1884.

Application filed January 24, 1884. (No model.)

To all whom it may concern:

Be it known that I, SOLOMON B. ELLITHORP, a citizen of the United States, residing at Rochester, in the county of Monroe and State of New York, have invented a new and useful Bran and Feed Packer, of which the following is a specification, reference being had to the accompanying drawings.

This invention relates to bran or feed packers; and it has for its main objects to pack and compress the material within the bags, sacks, and the like, and to expedite the filling of the bags, sacks, and the receptacles in general.

With these and other objects in view my improvements consist of an inner perforated cylinder and an outer non-perforated cylinder connected at their tops, forming an intermediate air-space, and the top connecting means 20 perforated for the escape of the air in the bran and the attached bag.

My improvement further consists in the combination of two vertical shafts—one within the other—carrying the package and compressing means and actuating mechanism.

My improvement further consists in the combination, with the double-walled cylinder with an intermediate air-space and the shafts carrying the package and compressing means, 30 of an automatic yielding bottom for supporting the bag to be filled.

My improvement further consists in the construction and combination of the vertical shafts—one vertically movable within the other—the packing devices, and the wipers.

My improvement further consists in the novel construction and combination of parts, as will be hereinafter more fully set forth.

In the annexed drawings, Figure 1 represents 40 a front elevation of my improved bran packer and compressor in connection with the feed-spouts. Fig. 2 is a plan view of the same. Fig. 3 is a partially sectional view of the vertical shafts, showing the relative arrangement thereof and their feeding devices or augers. Fig. 4 is a perspective view of the devices shown in Fig. 3 with gear-wheels attached; and Fig. 5 is a part sectional view of the perforated and non-perforated cylinders.

50 A represents the frame, preferably rectangular in shape, composed of the lower hori-

zontal bed-piece B, and the cap-piece C, connected together at a proper distance apart by the vertical rods a, firmly united to the lower bed-piece, B.

Arranged around the vertical rods a are coiled springs b, to give an elastic and yielding motion to the platform D, intermediately arranged on said rods between the bed-piece and cap-piece, substantially as seen in Fig. 1 of the drawings.

At a short and desired distance above the platform D, but under the cap-piece C, is supported the frame E, formed with a central opening, e, by means of the collars d, with set-screws surrounding the vertical rods a, and under the arms of the said frame E, substantially as shown in Fig. 1 of the drawings. The office of this frame E is for supporting a double-walled flanged cylinder F, to which the bag to be filled is attached.

The cylinder F consists of the inner perforated cylinder, e, made preferably of perforated sheet metal, the outer non-perforated cylinder, f, made preferably of sheet-iron, and the horizontal flange h, connecting the cylinders with an intermediate air-space, i. The horizontal flange is provided with a plurality of perforations, k, registering with the air-space i of the double-walled cylinder. The 80 perforations in the inner cylinder, e, and the horizontal flange h are to permit the escape of the air in the bran and the attached-bag during the process of packing and compressing the bran in the bag. Suspended within this double-walled cylinder F from the cap-plate C are two vertical shafts—one within the other—carrying the feeding and compressing means, as will be hereinafter more fully set forth.

To the central slotted bar of the cap-plate C 90 are secured adjustably the bearing l, for the upper end of the outer shaft, and the intermediate bearings, m, arranged on opposite sides of the central slotted bar, and also a suspended bearing, n, for the lower gear-wheel, p; also 95 to this central bar and the end bar are attached the upper and lower journal-bearings, r and s, for the horizontal shafts H and I, with gearing for operating the vertical shafts, substantially as shown in Fig. 1 of the drawings. 100 The lower horizontal shaft is provided with a gear-wheel, t, meshing with a gear, u, mounted

on the end of the upper horizontal shaft. The inner ends of these horizontal shafts are provided with bevel-gears v and w , engaging with the bevel-gears v' and w' , respectively, on the 5 vertical shafts. The bevel-gears v w are splined on the horizontal shafts, and are thrown into and out of gear by shifting levers operated automatically by mill machinery. (Not shown in the drawings.)

- 10 The vertical hollow shaft K has firmly secured to its lower end the auger or feed-plate L , which is constructed with two or more slots, x , and beveled lips y , for conducting the material below to the bag. This feeding-plate 15 L is further connected to the shaft by means of the collars z and curved wire rods 1, as shown in Figs. 3 and 4 of the drawings.

The shaft M , arranged within the vertical shaft K , is formed at its upper end with 20 screw-threads 2 and key or spline ways 3, and having swivelly connected at its lower end the auger or feeding-plate N , constructed like its companion plate L . These augers are connected by the vertical wires 4, fixed to the 25 lower auger, and passing upward loosely through perforations in the upper auger, to register the slots in the augers and cause both augers to revolve together in the rotary motion of the outer vertical shaft. The wire 30 rods 1 and 4 of the augers also serve the office of agitators in distributing and conducting the bran to the formed slots in the augers. The screw-threads of the inner vertical shaft, M , engage with the screw-threads of the collar 35 N^2 , supporting the upper bevel-gear.

Operation: The machine being properly organized and provided with a driving-pulley or its equivalent on the outer end of the lower horizontal shaft, a bag, sack, or the like is 40 pulled up over the bottom of the suspended double-walled cylinder, and the yielding platform, resting lightly against the bottom of the said cylinder, assists in retaining the bag in place as well as preserving the opened condition of the same. The bran or other material 45 is conducted through a spout leading from a reservoir into the upper end of the double-walled cylinder, and by the rotation of the feeding and packing means on the lower ends 50 of the vertical shafts the bran is kept in motion and worked downward into the bag. As the bag fills it depresses, gradually and automatically, the yielding platform supporting it, and automatically strips itself from the 55 holding-cylinder, until it is full, or nearly so. During this process of filling the bag, the air in the bran and bag escapes through the perforations of the inner cylinder and the horizontal flange, thereby allowing the bran to

become flattened and compressed. After the 60 bag is filled by the packing means, the compressing means are brought into play by the automatic shifting of the gearing, which causes the inner vertical shaft, with its bottom plate or auger, to descend for the purpose of compressing the bran more firmly within the bag and in a smaller space. By reversing the motion of the gearing and vertical shafts the 65 augers are brought together, and the machine is again in condition for another bag.

I reserve the right to vary the construction and arrangement of parts without departing from the spirit of the invention.

The yielding platform may be supported by cords and weights in lieu of the spiral springs.

What I claim as my invention, and desire to secure by Letters Patent, is—

1. In a bran-packer, the combination of the inner perforated cylinder, outer non-perforated cylinder, and horizontal perforated flange, 80 substantially as described.

2. In a bran-packer, the combination of the two upright shafts, one running within the other, as described, and for the purpose set forth.

3. In a bran-packer, an auger constructed in two parts, as described, and for the purpose set forth.

4. The combination of the double-walled cylinder and the two uprights with packing 90 devices, as described, and for the purpose set forth.

5. In a bran-packer, the combination of the adjustable auger and the two upright shafts, as described, and for the purpose set forth.

6. In a bran-packer, in combination with the vertical shafts and packing means revolving the agitators therewith, as described and set forth.

7. In a bran-packer, the combination of the 100 inner vertical shaft with the lower compressing-auger and the suspended cylinder supporting the bag, substantially as described.

8. In a bran-packer, the combination of the upright shafts, augers, agitators, and cylinders, for the purpose set forth.

9. In a bran or feed packer, the combination of a suspended cylinder, inside and outside upright shafts, with augers and agitators, and an automatic falling table, all as described, 110 and for the purpose set forth.

In testimony that I claim the foregoing as my own I have hereto affixed my signature in presence of two witnesses.

SOLOMON B. ELLITHORP.
